UNITED STATES PATENT OFFICE

WILLIAM H. DE BUSK, OF CHICAGO, ILLINOIS, ASSIGNOR TO THE P. & M. COMPANY, OF CHICAGO, ILLINOIS, A CORPORATION OF ILLINOIS.

RAIL ANCHOR.

Application filed July 25, 1924. Serial No. 728,070.

To all whom it may concern:

Be it known that I, WILLIAM H. DE BUSK, a citizen of the United States, residing at Chicago, in the county of Cook and State of Illinois, have invented certain new and useful Improvements in Rail Anchors, of which the following is a specification.

My invention relates to rail anchors of the type adapted to be applied to a railroad rail 10 in position to abut against a cross-tie or some other fixed portion of a track for holding the rail against movement longitudinally. It is the principal object of my invention to provide a new and improved form and arrangement of parts by the use of which an effective anchor may be produced at a minimum cost, and in which the operative gripping member may assume its operative gripping position without preliminary distortion beyond the expansion which is maintained in such final operative gripping position.

It is another object of my invention to provide an anchor in which a member is driven from one side of the rail into gripping engagement with the rail and into snap engagement with another member engaging the upper face of the flange at the opposite side of the rail whereby the gripping member is held normally against withdrawal transversely from the rail.

It is another object of my invention to provide a construction of the type above set forth in which both of the members are in the form of clips or gripping members which are driven from opposite sides of the rail into gripping engagement with the top and bottom faces of the flange of the rail at opposite sides thereof and are then secured together, preferably by snap engagement, for preventing them from backing transversely from the flange.

It is another object of my invention to improve devices of this type in sundry details hereinafter pointed out. The preferred means by which I have accomplished my several objects, are illustrated in the accompanying drawing and are hereinafter specifically described. That which I believe to be new and desire to cover by this application is set forth in the claims.

In the drawing—
Fig. 1 is a face view of my improved an-

chor in position on a rail shown in vertical cross-section and partly broken away;

Fig. 2 is a top plan view of the anchor of Fig. 1 partly in section;

Fig. 3 is a fragmentary view similar to a part of Fig. 2, but showing a changed position of the clip during the application of the anchor to the rail; and

Fig. 4 is a fragmentary view similar to a part of Fig. 1, but showing a modified form of construction.

This application is being filed as a continuation in part of my pending application Ser. No. 659,584, which was filed on August 27, 1923, as a division of my prior application Ser. No. 622,956, filed March 5, 1923, which latter application has resulted in U. S. Patent No. 1,476,802, granted December 11, 1923.

Referring to Figs. 1, 2 and 3, in which corresponding parts are indicated by the same reference characters,—10 indicates a rail resting upon a cross-tie 11. In position upon the rail, there is a member comprising a body 12, preferably formed of sheet metal, a jaw 13 in spaced relation with respect to the body at one end thereof, a depending plate 14 abutting against the cross-tie 11, and a shoulder 15 pressed into the upper face of the body 12. The jaw 13 is preferably formed by bending the end portion of the body blank backwardly upon itself, the space between the jaw and the body being insufficient normally to receive the rail flange, as is indicated by dotted lines in Fig. 1, the member being ordinarily applied to the rail by driving the member from the left in the drawing after having hooked the jaw 13 over the edge of the flange. The shoulder 15 is in position to snap into engagement with the side edge of the flange at the right in Fig. 1 when the jaw 13 has been moved into operative gripping position by driving as above described.

As is clearly shown in Fig. 2, the body 12 is cut away at the right to provide a deep notch 16, the notch being so positioned as to provide at one edge of the body a comparatively thin arm 17, provided on its free end with a shoulder 18.

When the member as above described has been driven into operative position on the

rail, with the plate 14 in engagement with the cross-tie 11, a clip 19 is driven into position upon the flange from the opposite side of the rail between the arm 17 and the body 12, the lower arm of the clip 19 being preferably tapered slightly to permit a ready insertion of the clip into its starting position on the flange, as is illustrated in Fig. 3. As will be readily understood, when the clip 19 is driven from the right in Fig. 3, the arm 17 is displaced slightly against the force of its resiliency, the proportions of the parts being such that when the clip reaches its final operative gripping position the shoulder 18 snaps into engagement with the outer face of the clip, as is best shown in Fig. 2.

As will be appreciated from an inspection of the drawing, if for any reason it is desirable to do so, the clip 19 can first be driven into position and the other member can thereafter be driven into operative position with respect to the clip and into operative gripping position on the flange. Ordinarily, however, the member comprising the body 12 and the abutment plate 14 is first driven into position with the plate 14 in contact with the cross-tie, and the clip member 19 then is applied as above described. In either event, the two members have snap engagement with each other just at the moment when first the two members are both in operative gripping position.

As is clearly indicated by dotted lines in Fig. 1, the opening between the arms of the clip 19 is normally insufficient to receive into operative position the flange of the rail. This clip is preferably to be formed of high-grade steel such that when it is driven into position the end of the upper arm will cut into the upper face of the flange, providing a transverse groove 20 in the face of the flange whereby the operative grip of the clip member for preventing longitudinal movement of the rail with respect thereto is enhanced.

Inasmuch as the clip 19 is made of high-grade steel, while the member 12 is preferably made of ordinary sheet-metal, it will be understood that the principal gripping effect is produced by the member 19. So far as I am aware, I am the first in the art to provide for driving a clip of this sort into operative position on a rail and at the same time into snap engagement with another member, the arrangement being such that the clip member is subjected to its greatest distortion when in its applied position and that the snap interengagement of the two members is effected by flexing a part of the member made of the lower grade metal until it snaps over a part of the other member.

In Fig. 4, which shows a modified form

of clip, corresponding parts are indicated by the same reference characters. In this construction, a clip 21 is provided, formed by stamping from a sheet of metal in lieu of the forged form as shown in the remaining figures. In the application of this form of clip, it is necessary to pry the arm 17 out of the way preparatory to the operation of driving the clip into operative position.

While I prefer to employ the form of device as shown in the drawing, it will be understood that I do not desire to restrict myself to that particular form, except as the same may be hereinafter specifically claimed, inasmuch as it is evident that changes may well be made in the form without departing from the spirit of the invention.

I claim:

1. A rail anchor comprising a member adapted to engage the upper face of the flange at one side of a rail, a second member adapted to be driven transversely of the rail from the opposite side thereof into gripping engagement with the rail, and a shoulder on one of said members having snap engagement with a part of the other member when the second member is driven into gripping position adapted normally to hold said second member against withdrawal from the flange.

2. A rail anchor comprising a member supported in operative position from the flange of a rail at one side thereof and held by the rail from movement toward the web of the rail, a second member adapted to be driven transversely of the rail from the opposite side thereof into gripping engagement with the rail, and means on one of said members adapted normally by engagement with a part of the other member to hold said second member against withdrawal from the flange.

3. A rail anchor comprising a member adapted to be hooked over the edge of the flange of a rail, a second member adapted to be driven transversely of the rail from the opposite side thereof into gripping engagement with the rail, and means on one of said members adapted to have snap engagement with the other member when said members are moved to their operative positions and adapted normally by such engagement to hold both members from withdrawal from the rail.

4. A rail anchor comprising a member of low grade metal supported in operative position from the flange of a rail at one side thereof and held by contact with the rail from movement inwardly toward the web, a second member of relatively much higher grade metal adapted to be driven transversely of the rail from the opposite side thereof into gripping engagement with the rail, and means on one of said members adapted to have snap engagement with the

other member when said members are moved to their operative positions and adapted normally by such engagement to hold both members from withdrawal from the flange of the rail.

5. A rail anchor comprising a member of low grade metal supported in operative position from the flange of a rail at one side thereof and held by contact with the rail from movement inwardly toward the web, a second member of relatively much higher grade metal adapted to be driven transversely of the rail from the opposite side thereof into gripping engagement with the rail, and a shoulder on said first-named member adapted to have snap engagement with the other member when said members are moved to their operative positions and adapted normally by such engagement to hold said members from withdrawal from the flange of the rail.

6. A rail anchor comprising a member of low grade metal adapted to be hooked over the edge of the flange of a rail, a second member of relatively much higher grade metal adapted to be driven transversely of the rail from the opposite side thereof into gripping engagement with the rail, and means on one of said members adapted to have snap engagement with the other member when said members are moved to their operative positions and adapted normally by such engagement to hold both members from withdrawal from the flange of the rail.

35 7. A rail anchor comprising a member adapted to engage the upper face of the flange at one side of a rail, a second member adapted to be driven transversely of the rail from the opposite side thereof into operative relation to said first-named member and into gripping engagement with the upper and bottom faces of the flange of the rail, and a shoulder on one of said members having snap engagement with a part of the other member when the second member is driven into gripping position adapted normally to hold said second member against withdrawal from the flange.

8. A rail anchor comprising a member supported in operative position from the flange of a rail at one side thereof and held by the rail from movement inwardly toward the web of the rail, a second member adapted to be driven transversely of the rail from the opposite side thereof into operative relation to said first-named member and into gripping engagement with the top and bottom faces of the flange of the rail, and means on one of said members adapted normally by engagement with a part of the other member to hold said second member against withdrawal from the flange.

9. A rail anchor comprising a member adapted to be hooked over the edge of the flange of a rail, a second member adapted to

be driven transversely of the rail from the opposite side thereof into operative relation to said first-named member and into gripping engagement with the top and bottom faces of the flange of the rail, and means on one of said members adapted to have snap engagement with the other member when said members are moved to their operative positions and adapted normally by such engagement to hold both members from withdrawal from the rail. 70 75

10. A rail anchor comprising a member of low grade metal adapted to be hooked over the edge of the flange of a rail, a second member of relatively much higher grade metal adapted to be driven from the opposite side of the rail transversely of the rail into operative relation to said first-named member and into gripping engagement with the top and bottom faces of the flange of the rail, and means on one of said members adapted to have snap engagement with the other member when said members are moved to their operative positions and adapted normally by such engagement to hold both members from withdrawal from the flange of the rail. 80 85 90

11. A rail anchor comprising a member applicable to a rail of a track out of contact with the cross-tie and engaging the upper face of the flange at one side of the rail, a second member adapted to be driven in contact with the cross-tie transversely of the rail from the opposite side thereof into operative relation to said first-named member and into gripping engagement with the rail, and a shoulder on one of said members having snap engagement with a part of the other member when said second member is driven into gripping position adapted normally to hold said second member against withdrawal from the flange. 95 100 105

12. A rail anchor comprising a member applicable to a rail of a track out of contact with the cross-tie and engaging the upper face of the flange at one side of the rail, a second member adapted to be driven in contact with the cross-tie transversely of the rail from the opposite side thereof into operative relation of said first-named member and into gripping engagement with the top and bottom faces of the flange of the rail, and a shoulder on one of said members having snap engagement with a part of the other member when said second member is driven into gripping position adapted normally to hold said second member against withdrawal from the flange. 110 115 120

13. A rail anchor comprising a member adapted to be driven transversely of the rail into gripping engagement with the top and bottom faces of the flange at one side of a rail, a second member adapted to be driven transversely of the rail into gripping engagement with the top and bottom faces of

- the flange at the opposite side of the rail, and means connecting said members together serving to hold both of them in operative position.
- 5 14. A rail anchor comprising a member adapted to be driven into gripping engagement with the top and bottom faces of the flange at one side of a rail, a second member adapted to be driven into gripping engagement with the top and bottom faces of the flange at the opposite side of the rail, and means carried by one of said members adapted to have snap engagement with the other member for holding said members against withdrawal from the rail.
- 10 15. A rail anchor comprising a member adapted to engage the upper face of the flange at one side of a rail, a second member adapted to be driven transversely of the rail from the opposite side thereof into gripping engagement with the rail, and a vertically-disposed shoulder resiliently carried by one of said members adapted to have snap engagement with a part of the other member when the second member is driven into gripping position and adapted normally to hold said second member against withdrawal from the flange.
- 15 16. A rail anchor comprising a member adapted to be hooked over the edge of the flange of a rail, a second member adapted to be driven transversely of the rail from the opposite side thereof into gripping engagement with the rail, and a vertically-disposed shoulder resiliently carried by one of said members adapted to have snap engagement with a part of the other member when the second member is driven into gripping position and adapted normally to hold said second member against withdrawal from the flange.
- 20 17. A rail anchor comprising a member adapted to engage the upper face of the flange at one side of a rail, a second member adapted to be driven transversely of the rail from the opposite side thereof into gripping engagement with the rail, a resilient arm carried by one of said members, and a shoulder on said arm adapted to have snap engagement with a part of the other member when said two members have been driven into final gripping position and adapted normally to hold said members from withdrawal from the flange.
- 25 18. A rail anchor comprising a member adapted to engage the upper face of the flange at one side of a rail, a second member adapted to be driven transversely of the rail from the opposite side thereof into gripping engagement with the rail, a resilient arm carried by one of said members and extending transversely of the rail adapted to be displaced longitudinally of the rail, and a shoulder on said arm adapted to have snap engagement with a part of the other member when the second member is driven into gripping position adapted normally to hold said members from withdrawal from the flange.
- 30 19. A rail anchor comprising a member of low grade metal adapted to be hooked over the edge of the flange of a rail, a second member of relatively much higher grade metal adapted to be driven transversely of the rail from the opposite side thereof into gripping engagement with the rail, and means carried by the member of low grade metal adapted to snap into engagement with a part of the other member when said members have been moved to their operative positions and adapted normally by such engagement to hold both members from withdrawal from the rail.
- 35 20. A rail anchor comprising a member of low grade metal supported in operative position from the top face of the flange of a rail at one side of the rail and held by contact with the rail from movement inwardly toward the web, a second member of relatively much higher grade metal adapted to be driven transversely of the rail from the opposite side thereof into gripping engagement with the top and bottom faces of the rail, a resilient arm carried by said first-named member and extending transversely of the rail adapted to be displaced longitudinally of the rail, and a shoulder on said arm adapted to have snap engagement with a part of the second member when said two members have been driven to their operative positions and adapted normally to hold said members from withdrawal from the flange.
- 40 21. A rail anchor comprising a member adapted to engage the upper face of the flange of a rail at one side thereof, a bearing plate depending from said member for engagement with a cross-tie, a second member adapted to be driven transversely of the rail from the opposite side thereof into operative relation with respect to said first-named member and into gripping engagement with the top and bottom faces of the flange of the rail, and a shoulder on one of said members having snap engagement with a part of the other member when the second member is driven into gripping position adapted normally to hold said members from withdrawal from the flange.
- 45 22. In a rail anchor, the combination of a member comprising a body formed of sheet metal, an integrally formed jaw on one end of the body adapted to engage the flange at one side of a rail, and an integrally formed plate depending from the body for engaging the cross-tie, a second member adapted to be driven transversely of the rail from the opposite side thereof into operative relation with respect to said first-named member and into gripping en-

5

gagement with the top and bottom faces of the flange of the rail, and a shoulder on one of said members having snap engagement with a part of the other member when said two members have been moved to their operative gripping positions adapted normally to hold said members from withdrawal from the flange. 23. In a rail anchor, the combination of a member formed of sheet-metal and comprising a body, a jaw on one end of the body adapted to engage the flange at one side of the rail, a plate depending from the body for engaging the cross-tie, an arm on said body extending transversely of the rail, and a shoulder on said arm adapted to be displaced longitudinally of the rail against the resiliency of the arm, with a second member adapted to be driven transversely of the rail from the opposite side thereof into operative relation with respect to said first-named member and into gripping engagement with the top and bottom faces of the flange of the rail, said shoulder being adapted to have snap engagement with the outer face of the second member when said two members have been moved to their operative positions and being adapted normally to hold said two members from withdrawal from the flange. 24. A rail anchor comprising a member adapted to engage the base portion of a rail, a second member adapted to be distorted to effect a grip on the rail and adapted to be subjected to its greatest distortion when in its applied position, and means on one of said members adapted to have snap engagement with the other member to prevent withdrawal of said members from the rail. 25. A rail anchor comprising a member adapted to engage the base portion of a rail, a second member adapted to be distorted to effect a grip on the upper surface of the flange of the rail at one side of the rail and adapted to be subjected to its greatest distortion when in its applied position, and means on one of said members adapted to have snap engagement with the other member and adapted normally by such engagement to hold said members against withdrawal from the rail. 26. A rail anchor comprising a member adapted to engage the opposite edge portions of the base portion of a rail, a second member adapted to be distorted to effect a grip on the upper surface of the flange at one side of the rail base and adapted to be subjected to its greatest distortion when in its applied position, and means on one of said members adapted to have snap engagement with the other member and adapted normally by such engagement to hold said members against withdrawal from the rail. 27. A rail anchor comprising a member adapted to engage the base portion of a rail, a second member adapted to be distorted to effect a grip on the upper surface of the flange at one side of the rail base and adapted to be subjected to its greatest distortion when in its applied position, and means on one of said members adapted to have snap engagement with the other member and adapted normally by such engagement to hold said members against withdrawal from the rail. 28. A rail anchor comprising a member adapted to engage the base portion of a rail, a second member adapted to be distorted to effect a spring grip on the upper and lower surfaces of said base at one side thereof and adapted to be subjected to its greatest distortion when in its applied position, and means on one of said members adapted to have snap engagement with the other member and adapted normally by such engagement to hold said members in their operative positions. 29. A rail anchor comprising a member provided at opposite ends with means for engaging opposite edge portions of a rail base, a second member adapted to be distorted to effect a spring grip on said rail base at one side thereof and adapted to be subjected to its greatest distortion when in its applied position, and means on one of said members adapted to be flexed longitudinally of the rail to effect an interlocking engagement of said members. 30. A rail anchor comprising a rail gripping member formed with two arms in spaced relation with each other adapted to spread apart by the application of said member to the flange of a rail, and a retaining member comprising a bar formed at one end with means for engaging the edge of a flange at the opposite side of the rail and at the other end with means for engaging said rail gripping member to hold the gripping member from backing transversely from the rail. 31. A rail anchor comprising a gripping member engaging one side only of a rail, and a second member adapted by engagement with said first named member and with the flange at the opposite side of the rail to hold said first named member in operative position, said second member being adapted when the anchor is applied to the rail to snap by its resilience into operative holding position. 32. A rail anchor comprising a member adapted to be driven into gripping engagement with the top and bottom faces of the flange of a rail at one side only, and a second member extending from said first named member into engagement with the flange at the opposite side of the rail to hold said first named member in operative position, said second member being adapted when the anchor is applied to the rail to

snap by its resilience into operative holding position.

33. A rail anchor comprising a member adapted to be driven into gripping engagement with the top and bottom faces of the flange of a rail at one side only, and a second member formed integrally from a single piece of resilient metal adapted by engagement with said first named member and 10 with the flange at the opposite side of the rail to hold said first named member in operative position, said second member being held in position by resilient snap engagement without permanent distortion thereof.

34. A rail anchor comprising a member 15 adapted to be driven into gripping engagement with the top and bottom faces of the flange of a rail at one side thereof and adapted by engagement with a cross tie to resist longitudinal movement of the rail with 20 respect to the cross tie, and a second member formed integrally from a single piece of resilient metal adapted by engagement with said first named member and with the flange at the opposite side of the rail to hold said 25 first named member from backing transversely of the rail from the flange.

WILLIAM H. DE BUSK.
